UNITED STATES PATENT OFFICE.

LLEWELLYN H. STARKEY, OF NEW YORK, N. Y.

DIAL.

No. 919,262.

Specification of Letters Patent.

Patented April 20, 1909.

Application filed January 2, 1909. Serial No. 470,424.

To all whom it may concern:

Be it known that I, LLEWELLYN H. STARKEY, a citizen of the United States, and a resident of New York, in the county of 5 New York and State of New York, have invented certain new and useful Improvements in Dials, of which the following is a specification, taken in connection with the accompanying drawing, which forms a part 10 of the same.

This invention relates to dials and more particularly to non-circular dials for time or other recording instruments.

In the accompanying drawing showing 15 illustrative embodiments of this invention and in which the same reference numerals refer to similar parts in the several figures, Figure 1 is an end elevation of a clock equipped with one form of my new and improved dial. Fig. 2 is a plan view of another form of non-circular dial.

Prior to my invention all dials for clocks or other recording instruments which had rotatable indicating arms or hands were provided with circular dials, near the circumference of which were located the usual numerals and minute marks. To provide a 25 clock or other recording instrument having an oval or non-circular face with a dial to 30 coöperate with the rotatable indicating arms or hands it is customary to provide a circular dial, the diameter of which is substantially the same as the shortest axis of the face of the clock or other instrument. This leaves 35 on the longest axis blank crescent shaped spaces between the dial and the frame.

My invention broadly consists in making the symbols and minute marks upon any 40 non-circular dial coöperative with a rotatable indicating hand or arm or with two or more such hands or arms so that they will approximately touch each of the symbols or minute marks and in that manner correctly indicate the time, if the dial is used for instance with a clock mechanism, though it 45 is to be understood that my dial is not to be limited to such use.

In the illustrative embodiments of this invention, which for purposes of illustration and 50 description is shown applied to a clock, 1 is a non-circular dial formed preferably in the shape of an oval to exactly fit the oval opening in the face 2 of the clock which is provided with legs or supports 3, 3. The dial 1 55 is provided with symbols representing the different hours from 1 to 12, and with minute

marks which extend substantially from the outer circumference of the dial inward. These symbols are shown as Arabic numerals, but it is to be understood that Roman 60 numerals or any other symbols may be used. In the form of dial shown in Fig. 1, these symbols are of graduated length or height, the largest being upon the longest axis of the dial, which, in this form, are the numerals 12 65 and 6, the shortest numerals, 3 and 9, being located on the shortest axis. The other numerals are graduated in height or length between these extremes. I also preferably arrange the symbols or numerals to extend 70 inward from the circumference of an imaginary and smaller ellipse or oval drawn on the face of the dial, its center being the same as that of the dial. The spaces between the different numerals or symbols, designating 75 in this form of my invention the hours, are divided into five substantially equal parts and each part is bounded by minute marks drawn from the outer circumference of the oval or ellipse inward. These lines 4, 4 are 80 given different lengths depending upon their position on the face of the dial; those appearing for instance, between the numerals 8 to 10 and 2 to 4 are of approximately the shortest length and those appearing between 85 the numerals 11 to 1 and 5 to 7 are of approximately the longest length. Moreover, in the oval form of my invention, the distance between the points on the circumference of the oval designating approximately 90 the center of the different symbols will vary and necessarily the distance between the different minute marks will also vary. For instance, the distance between the points 5 and 6 upon Fig. 1 will be shorter than the 95 distance between 7 and 8, which will necessitate the minute marks, 4, 4 being placed at a greater distance from each other between the points 7 and 8 than between the corresponding points 5 and 6. Additional marks 12 100 may be used to indicate half minutes and quarter minutes, if desired, may also be used. It will therefore be seen that besides forming a pleasing and artistic dial, the entire oval or non-circular face of the clock 105 shown in Fig. 1 is taken up by my oval dial and that upon each revolution of the hour hand 10, it will approximately touch the symbols and upon each revolution of the minute hand 9 it will approximately touch 110 both the symbols and the minute marks and in that manner correctly indicate the time.

It is, of course, to be understood that my invention is not limited to the symbols being placed in any particular manner upon the face of the dial, for they may be readily placed as shown in Fig. 2 wherein the symbols or numerals 6 and 12 upon the dial 11, are located upon the shortest axis of the dial 11 and the numerals 3 and 6 upon the longest, which is the exact reversal of the form shown in Fig. 1. This arrangement, of course, will entail the longest minute and half minute marks being placed in proximity to the numerals 3 and 9 and the shortest minute and half minute marks in proximity to the numerals 6 and 12, as will be readily understood.

Though I have shown my invention as an oval or elliptical dial it is to be understood that broadly my invention comprises a non-circular dial of any shape which is provided with symbols and marks such as minute and hour symbols to coöperate with an indicating arm or pointer moving in a circular path.

My dial may be used with any recording mechanism which has one or more rotatable arms or pointers and it may be either en-

graved, drawn, carved, stenciled, painted or printed on any suitable substance or otherwise made, as may be found convenient or expedient.

Having thus described this invention in connection with the several illustrative embodiments thereof to the details of which I do not desire to be limited, what is claimed as new and what it is desired to secure by Letters Patent is set forth in the appended claim.

A substantially oval dial for clocks, watches or other recording instruments, provided with spaced symbols extending inward from an imaginary and smaller ellipse drawn on the face of the dial, said symbols varying in size, the largest being approximately on the longest axis of the dial and the smallest on the shortest axis, minute spaces of unequal width between the different symbols and minute marks of varying lengths.

LLEWELLYN H. STARKEY.
